ROTATABLE RACK AND SUPPORT

John Woda, Los Angeles, Calif.

Application August 15, 1935, Serial No. 36,414

3 Claims. (Cl. 211—95)

This invention relates to certain new and useful improvements in rotatable racks and supports, particularly intended for receiving neckties and other articles of apparel of a long slender nature.

5 The primary object of this invention is to provide a rotatable garment support adapted to be easily attached to a wall or other vertical support or the device may be stored for transportation by folding the hinged sections to a compact position.

10 A further object of this invention is to provide a rotatable support including a hub having radial prongs for receiving articles of apparel or garments and surrounding the radial supporting pin is a retainer ring for preventing the articles of apparel from being misplaced after they have once been placed in position.

15 A still further object of the invention is to provide a device of the above mentioned character in which the retaining ring is placed about the radial supporting pin to completely confine the same with the exception of an interruption adapted to allow the placing and removing of articles of apparel upon the rack.

20 Other objects and advantages of the invention will become apparent during the course of the following description, taken with the drawing, wherein,

25 Figure 1 is a top elevational view of the device embodying this invention;

30 Figure 2 is a front elevational view illustrating the rack supporting member in its extended position;

35 Figure 3 is a side elevational view of the garment support showing the same in position for attachment to a wall or other vertical surface;

Figure 4 is a side elevational view of the garment supporting rack illustrating the same in its folded position for transportation;

40 Figure 5 is a vertical cross-sectional view greatly enlarged, taken on line 5—5 of Figure 1, looking in the direction of the arrows.

45 Illustrating the pivot pin connection between the hinged arm and the rotatable supporting member,

Figure 6 shows side and end views of a screw connection between the bracket and frame, and

50 Figure 7 fragmentarily illustrates a pin and key slot connection between the bracket and frame.

In the drawing, wherein for the purpose of illustrating the invention, and wherein like reference characters will be employed to designate like parts throughout the same, the reference character 5 will generally be employed to desig-

nate a wall bracket having openings 6 for receiving fastening elements such as screws or the like for securing the bracket to a wall or other support. Formed centrally in the bracket 5 is an opening 7 for accommodating the passage of certain parts of the rack when in its folded position whereby the latter may assume a compact form for shipment or other purposes.

Hinged to the upper end of the wall bracket 5 is a tapering arm 8 having an upstanding extension 9 that projects beyond the inner end of the arm and which is of less diameter than the arm for pivotal reception between projections 10 rising from the upper end of the bracket 5. A pintle 11 extends through the projections 10 and the extension 9 to permit pivotal movements between the arm 8 and bracket 5.

Rotatably secured to the hinged arm 8 is a hub 12 having a circumferential series of spaced radially projecting prongs or pins 13 on the periphery 20 of the hub and upon which may be placed articles of apparel such as neckties, stockings, and other slender articles. The mounting for the hub 12 includes a bottom 15 located above the free end 25 of the arm and carrying a depending pin 14 journalled in the arm and extending through the hub as shown in Figure 5. The lower end of the pin is fixed to the hub by means of a wedge connection including the splitting of the lower end of the pin 14 at 14^a and the insertion of a wedge 30 piece 14^b into the split end of the pin below the hub 12. A washer 16 is interposed between the hub 12 and the hinged arm 8 for preventing contact of the hub with the arm 8 and facilitating free rotary movement of the hub.

35 Encircling the hub 12 and in proximity of the outer ends of the pins 13, is a retaining ring 19 having an interrupted portion and said retaining ring 19 is anchored to the hinged arm 8 by fastening screws 20 which connect the extension 9 40 to the hinged arm 8. The free spaced ends 21 of the retaining ring 19 are at a point diametrically opposite the anchor point, thereby providing a space for the placing and removal of articles to and from the supporting pins 13.

45 The device may be formed of metal or wood and may be painted or decorated in attractive colors to add to the appearance and ornamental design of the rack.

When the device is in its folded position as 50 shown in Figure 4, the opening 7 receives the operating knob 15 so that the device may be stored within a suitcase or other luggage container and occupying a minimum of space. The structure is in its unfolded position for attachment to 55

a wall as clearly shown in Figures 1, 2 and 3, the hinged supporting arm 8 is moved 270° from the position shown in Figure 4 and said arm is supported in the position by means of the anchored 5 side of the retaining ring engaging the bracket 5.

Articles of apparel may be supported upon the supporting pins 13 and the knob 15 rotated to cause the articles thus placed in position to be moved away from the opening formed by the 10 spaced ends 21 of the ring. The device may support as many articles of apparel as there are supporting pins 13 and such articles of apparel are prevented from displacement by means of the retaining ring 19 which confines the supporting 15 pins and prevents radial movement of articles placed thereon as will be evident from an inspection of Figure 1. When it is desired to remove articles from the supporting pins, the knob 15 is rotated until the desired article is brought into 20 registry with the opening or space formed by the ends 21 whereupon the article of apparel may be easily removed from such supporting pins.

In the form of frame structure illustrated in 25 Figure 6, the bracket 5^a is adapted to be rigidly attached to the arm 8^a by means of screws 11^a securing the upper end of the bracket to the inner end of the arm.

As shown in Figure 7, the inner end of the 30 retaining ring 19^b carries a pair of headed pins 11^b to be received in key slots 11^c in the upper end of the bracket 5^b, the latter being detachable from the frame structure for purposes of storing or shipment.

It is to be understood that the forms of the invention herewith shown and described are to be taken as preferred embodiments of the same and that various changes in the shape, size, and arrangement of parts may be resorted to without departing from the spirit and scope of the invention as claimed. 5

I claim:—

1. A supporting rack comprising a wall bracket, an arm hingedly secured to the wall bracket, a 10 hub rotatably secured to the hinged arm, radially extending pins for receiving articles of apparel attached to the hub, and an interrupted ring 15 confining the supporting pins attached to the hinged arm.

2. An article supporting rack of the character described, comprising a wall bracket, an arm hingedly secured to the upper end of the wall bracket, a disk pivotally secured to the free end 20 of the hinged arm, radially extending pins secured to the pivoted disk, an interrupted ring having its portion opposite the interruption connected to the hinged arm, and a knob for operating the rotary disk. 25

3. An article support of the character described, comprising a wall bracket, an arm hingedly secured to the upper end of the wall bracket, a disk pivotally secured to the free end 30 of the hinged arm, a knob for rotating the disk, radially extending pins connected to the disk, and an interrupted ring secured to the hinged arm adapted to confine the majority of the radially extending pins.

JOHN WODA.
